William Baker,

By *J. James Talbert*

His Attorney.

UNITED STATES PATENT OFFICE.

WILLIAM BAKER, OF CINCINNATI, OHIO.

SCRUB BRUSH.

Application filed February 23, 1924. Serial No. 694,622.

To all whom it may concern:

Be it known that WILLIAM BAKER, a citizen of the United States of America, residing at Cincinnati, in the county of Hamilton and State of Ohio, has invented new and useful Improvements in Scrub Brushes, of which the following is a specification.

At present, a bucket and sponge are used for scrubbing floors and walls and especially those of railroad cars, and to avoid this tedious method, it is the purpose of the present invention to provide, in a scrub brush, a construction for keeping the brush supplied with water and soap, the brush having a handle whereby the operator may easily manipulate the brush and thereby insure reaching all parts of the surfaces being scrubbed.

Another purpose is to provide a pair of brushes rigidly connected, with a perforated supply pipe for the water mounted between certain of the bristles of the brush, in conjunction with liquid soap fountains or containers having perforations registering with perforations in the backs of the brushes to keep the bristles thoroughly supplied with soap.

Still another purpose is the provision of means for retaining the fountains or containers on the backs or wood portions of the brushes.

A further purpose is the provision of means for rigidly securing the handle to and connecting the backs of the brushes to insure rigidity, the perforated pipe further insuring strength and durability.

A still further purpose is to provide a scrub brush of this design wherein a metallic tubular handle is connected to the brush for operating the same, together with means for connecting a water supply hose to said handle to keep the brush supplied with water.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a plan view of the improved

scrub brush constructed in accordance with the invention.

Figure 2 is a longitudinal sectional view through the two sections of the brush.

Figure 3 is a plan view of the brush.

Figure 4 is a transverse sectional view on line 4—4 of Figure 2.

Figure 5 is a plan view of the brush, showing the tubular handle which is adapted for connection with a hose which supplies water to the brush.

Referring to the drawings, 1 and 2 designate the two sections of the brush. The backs of the sections may be constructed of any suitable material, preferably wood or metal, and are provided with rows of bristles 3. The backs of the sections of the brush between the rows of bristles are perforated, as shown at 4, and mounted upon the backs are fountains 5 for receiving liquid soap. The fountains are rectangular in cross section and have their bottoms provided with perforations 6 which register with perforations 4 in the backs of the sections of the brush.

The fountains seat in depressed recesses 7 in the backs of the brush sections, there being a filler of rubber in the bottoms of the recesses to prevent leakage. Suitable U-shaped stays or straps 8 straddle the fountains, the arms of the straps passing through openings in the backs of the brush sections, there being suitable nuts 9 threaded upon the arms to hold the straps securely in position and retain the fountains clamped to the backs of the brush sections. The fountains are provided with filling openings 10 which are closed by caps 11.

As shown in Figures 1 to 4, a handle 12 is provided which engages a socket 13 of a handle coupling device 14. This device has lateral arms 15 which are secured by screws or the like 16 to the backs of the brush sections, thereby holding the brush sections rigidly in alignment. The handle is disposed at an angle to the brush sections so that the operator may readily manipulate the brush over the surfaces to be washed.

Also carried by the backs of the brush sections between the central rows of bristles are perforated pipes 17 which are secured in any suitable manner to the backs of the brush sections. The perforations of these pipes are positioned so as to direct water therefrom divergently when the brush sections are moving over the surface being scrubbed. These

pipe sections are connected by a T-union 18 and due to the pipe sections being secured to the backs of the brush sections and since the union constitutes a coupling device, the pipe sections and the coupling device additionally insure rigidity between the brush sections.

Connected to one leg of the T-union is a nipple 19 to which a reducer 20 is connected. A hose 21 connects with the reducer and is 10 provided with a suitable valve or cut-off 22 for controlling the supply of water to the brush during the operations of the brush. The hose may be of the general construction and may connect with any suitable 15 source of supply, such as is provided with a main control valve 23, for turning off the supply of water when finishing with the use of the brush.

In Figure 5, it will be noted that the T-union 24 is slightly modified and connected to one leg of the union is an elbow 25 to which a short pipe section 26 is connected. A second elbow 27 is connected to the short pipe section 26 and carries a long tubular 25 pipe section 28 which constitutes a handle and to which the hose may be connected for supplying water to the brush, which is identical in construction with that shown in Figures 1 to 4. By this method of connecting 30 the handle 28 to the brush, it is possible to supply the water through the handle and yet allow the handle to move relative to the brush as it is moving over the surface being washed.

35 The invention having been set forth, what is claimed is:

1. In a scrub brush, the combination with a pair of aligned brush sections, of a handle holder connecting the brush sections, the 40 backs of the brush sections provided with perforations, fountains on the backs and adapted to contain liquid soap to supply the soap to the bristles through the perforations, and means for supplying water to the 45 bristles of the brush sections.

2. In a scrub brush, the combination with a pair of aligned brush sections, means connecting the backs of the brush sections, the backs of the brush sections having depressed 50 seats with perforations in their bottoms,

fountains with perforations in their bottoms engaged in said depressed seats, whereby the perforations of the fountains and the backs of the brush sections may register to supply liquid soap to the bristles of the 55 brush sections, and means for supplying water to the bristles of the brush sections.

3. In a scrub brush, a pair of brush sections provided with depressed recesses, liquid soap fountains seated in said recesses 60 and provided with means to insure retaining the fountains in the recesses, said fountains having passages of communication with the spaces between the bristles of the brush sections to supply liquid soap to the bristles, a 65 handle holder connecting the brush sections to hold them rigid, and means to supply water to the bristles.

4. In a scrub brush, a pair of brush sections provided with depressed recesses, 70 liquid soap fountains seated in said recesses and provided with means to insure retaining the fountains in the recesses, said fountains having passages of communication with the spaces between the bristles of the 75 brush sections to supply liquid soap to the bristles, a handle holder connecting the brush sections to hold them rigid, means to supply water to the bristles, said last named means comprising spray pipe sections 80 disposed between the central bristles of the brush sections, a T-union connecting the perforated pipe sections, and means for securing the pipe sections to the backs of the brush sections, said T-unit having means 85 whereby a water supply hose may be coupled thereto.

5. A scrub brush comprising a pair of aligned brush sections having liquid soap supplying means mounted upon the backs of 90 the brush sections, aligned perforated pipe sections secured to the backs of the brush sections between the central bristles of the brush sections, and a union connecting the perforated pipe sections and having means 95 whereby a water supply may connect with the union.

In testimony whereof he affixes his signature.

WILLIAM BAKER.
